UNITED STATES PATENT OFFICE.

GEORGE F. SISBOWER, OF EAST ORANGE, NEW JERSEY, AND LOUIS EDWARD PITTONI, OF NEW YORK, N. Y., ASSIGNEES TO NEW YORK COUCH BED COMPANY, OF NEW YORK, N. Y., A CORPORATION OF NEW YORK.

FOLDING-BED STRUCTURE.

1,229,536.

Specification of Letters Patent. Patented June 12, 1917.

Application filed November 19, 1912. Serial No. 732,366.

To all whom it may concern:

Be it known that we, GEORGE F. SISBOWER, a citizen of the United States, residing at East Orange, in the county of Essex and State of New Jersey, and LOUIS EDWARD PITTONI, a subject of the King of Italy, residing at New York city, county and State of New York, have invented certain new and useful Improvements in Folding-Bed Structures, the following being a full, clear, and exact disclosure of the one form of our invention which we at present deem preferable.

For a detailed description of the present form of our invention, reference may be had to the following specification and to the accompanying drawing forming a part thereof, in which—

Figure 1 is a perspective view of one end of our structure in a partially closed position;

Fig. 2 is an end elevation of the structure in its open position, and

Fig. 3 an end view of it in its closed position.

Our invention relates to a folding bed structure which may be employed for a chair or davenport on the one hand or converted into a bed on the other hand. In particular, we have endeavored to devise a structure which may be cheaply constructed of metal parts and which will be simple in form, easy and certain in operation.

Our structure comprises three parts or sections, two of which are swinging sections and one a horizontally moving section. One of the swinging sections is hinged at some intermediate point, preferably near its center, to the main frame and the other is hinged to the horizontally movable section.

The two swinging sections are also hinged together at their adjacent edges by a short link and carry a mattress adapted to be folded between them while the opposite side of the central section is upholstered or carries a mattress adapted to form the back of the chair or davenport and the upper side of the horizontally movable frame is also upholstered or carries a mattress to form the seat of the said chair or davenport.

The horizontally moving section is supported at its front edge by legs with casters reaching to the floor and at its rear edge by short legs with rollers traveling on horizontal trackways formed by cross-bars on the main frame.

Referring to the drawing, it will be understood that, while but one end of our device is shown therein, the opposite end will be like it. A represents an end frame of tubular metal in the form of an inverted U, with its legs connected by cross-bars B and C, the latter being of angle iron. The two opposite end frames are connected longitudinally by a flat bar D in the rear and in the front by an angle bar D¹. The working parts include three movable sections 1, 2 and 3 of which section 1 is upholstered on both sides and sections 2 and 3 on one side only. The frame 3_a of section 3 is provided with legs and casters 3_b at its forward edge, and at its rear edge it has short legs E having rollers running on a trackway formed by the horizontal flange of the angular cross-bar C. By this means the section 3 can roll in and out with respect to the main frame. The section 2 has its frame 2_a pivoted at its center on the end frame A at the point 4, being thus in a balanced condition easily movable on its pivots. The section 1 has its frame 1_a provided with lugs P pivoted to upward extensions of the legs E, on the horizontally movable section, while it is connected at its rear edge to the section 2 by means of short links K. To the inner edge of the frame 2_a is pivoted a supporting bar F having at its lower end a step or offset F¹ adapted to rest on the cross-bar B and support the inner edge of section 2 when it is in its horizontal position, as shown in Fig. 2. The bar F is connected by a link G to a long latch lever H which is pivoted to the frame 3_a at the point 5. This latch H, when the structure is closed or folded, as in Fig. 3, hooks over a pin T on the frame 2_a of the section 2 and is also connected by the link G to the supporting bar F on the section 2, so that the in-and-out movement of section 3 will bring the supporting bar into a vertical position as shown in Fig. 2, wherein it supports the sections 1 and 2 which are then opened out or extended to form a bed, or it will bring the bar into the inactive position shown in Fig. 3.

The operation of our device will be readily understood from the drawing. Assuming the structure to be in its folded or closed position, as in Fig. 3, the two swinging sections 1 and 2 will be in their vertical position, the former presenting its shorter length of mattress or upholstery to form the back

of a chair or davenport, while the bed mattress, which in the open condition shown in Fig. 2, extends across both of the sections 1 and 2, is now folded in between the two frames 1_a and 2_a. The horizontally moving section is at the innermost point of its travel, with the latch H engaging the pin T and the supporting bar F in a nearly horizontal position. To open out the structure into bed form, it is only necessary to depress the outer end of latch H and draw forward the horizontally movable section, when the two sections 1 and 2 will unfold, as shown in Fig. 1, swinging on their respective pivots, while the section 1 will also move bodily forward until it lies out horizontally, as shown in Fig. 2, upon the section 3, being supported thereby, while at the same time the bar F is turned forward until it comes into its vertical supporting position shown in Fig. 2. To close the structure, the section 1 will be lifted at its outer edge and folded up against section 2 which is simultaneously swung into its vertical position, while the section 3 is also moved inward simultaneously till the latch H engages pin T.

What we claim as new and desire to secure by Letters Patent is:

30. 1. As an improvement in a folding bed structure, two spaced apart movable sections each upholstered on one side, and a third section interposed between and movably connected with the first mentioned sections, said third section being upholstered on both sides and coöperating alternately with the first mentioned sections to present two separate usable upholstered surfaces.

40. 2. An improved folding bed structure comprising a supporting frame, a horizontally movable section, supports for the inner side of said section, said supports slidably engaging said frame, a second section pivotally attached to said frame, and a third section pivotally connected to said slidable supports and movably connected with the second section.

50. 3. The combination in a folding bed-structure of two hinged-together swinging sections, one upholstered on both sides, the other on one side and both forming, when in vertical parallel relation, the back of a chair or davenport, and a horizontally movable section hinged to an intermediate point of the section which is upholstered on both sides and serving to support the same when the structure is extended but to form the seat of the chair or davenport when the structure is folded.

60. 4. The combination in a folding bed-structure of two swinging sections and one horizontally movable section, one of the swinging sections being hinged to the framework

of the structure and the other one hinged at an intermediate point in its width to the horizontally movable section.

5. The combination in a folding bed-structure of two swinging sections and one horizontally movable section, one of the swinging sections being hinged at a point intermediate of its width to the framework of the structure and the other being hinged, also at a point intermediate of its width, to the horizontally movable section, and a hinge connection between the adjacent edges of the two swinging sections.

6. The combination in a folding bed-structure of two swinging sections hinged together at their adjacent edges to form a bed when extended in their horizontal position, a support for one section when in said position formed by a third horizontally moving section, and an auxiliary support at an intermediate point in the width of the frame of the structure formed by a vertical bar resting on a bar of the said framework and pivoted to one of the two swinging sections.

7. The combination in a folding bed-structure of two swinging sections hinged at intermediate points in their width, one to the framework of the structure, the other to a horizontally movable part, hinge connections between the adjacent edges of said sections, and supports for maintaining said sections in a horizontal unfolded position.

8. The combination in a folding bed-structure of two swinging sections, a horizontally movable section to which one of said swinging sections is hinged, the other being hinged to the main frame, and a depending support-bar hinged to one of the swinging sections and linked to the horizontally movable section so as to be thereby brought into or out of its supporting position.

9. The combination in a folding bed-structure of end frames, each having a horizontal trackway, a horizontally movable section having legs and casters on one edge and its other edge adapted to travel on said trackways, two swinging sections, one hinged to the main frame, the other to the horizontally movable section, a link joining the adjacent edges of the swinging sections, a supporting bar hinged to one of the swinging sections and reaching therefrom to a cross-bar on the end frame and adapted to bear thereon and a connecting device between said supporting bar and the horizontally movable section.

In witness whereof we have hereunto set our hands before two subscribing witnesses, this thirteenth day of November, 1912.

GEORGE F. SISBOWER.
LOUIS EDWARD PITTONI.
